UNITED STATES PATENT OFFICE.

RICHARD P. WHITE, OF CHICAGO, ILLINOIS.

PACKAGE FOR STONEWARE OR THE LIKE.

Application filed April 1, 1922. Serial No. 548,665.

To all whom it may concern:

Be it known that I, RICHARD P. WHITE, a citizen of the United States, and resident of Chicago, county of Cook, and State of Illinois, have invented certain new and useful Improvements in Packages for Stoneware or the like, of which the following is a specification and which are illustrated in the accompanying drawings, forming a part thereof.

The invention relates to packing heavy fragile articles such as stoneware, thick glassware, and the like for shipment or rough handling at any time. As heretofore practiced, the cost of providing a safe packing for these articles is quite out of proportion to their value and the loss by breakage in shipment and handling is excessive. The invention accordingly has for its object a package for stoneware and like articles designed to furnish an effective protection against breakage, especially by contact with other articles of the same shape and kind, without being of such elaborate construction that its cost is a material item in proportion to the value of the article or its weight excessive. To this end the invention contemplates a package or covering which may be applied to the article and firmly held thereon for receiving the blows and shocks which would otherwise be most likely to be directly effective upon the article without completely enclosing the same. Under these circumstances the article may, if preferred, be displayed for sale and, in some forms, used as desired while protected by the package.

In the accompanying drawings—

Fig. 1 is a perspective view showing one form of the improved package as applied to a stone jar;

Fig. 2 is a detail plan sectional view taken on the line 2—2 of Fig. 1;

Fig. 3 is a detail vertical sectional view of the package and article shown in Fig. 1;

Figs. 4 and 5 are each similar to Fig. 3, but show modified forms of the package and slight modifications in the form of the article;

Fig. 6 is a perspective view showing a further modification, the package and article being separated to facilitate illustration, and

Fig. 7 is a perspective view similar to

Fig. 1, but partly in section and showing another form of package.

The improved package preferably comprises one or more bands or hoops, as 10, 11, (Fig. 1) and (Fig. 3), 14, 15, (Fig. 4), 16, 17 (Fig. 5), 18 (Fig. 6) or 19, 20 and 21 (Fig. 7). These bands may be formed from any suitable inexpensive material, the bands illustrated in Figs. 1 to 6 inclusive being wood and those illustrated in Fig. 7 being formed from corrugated paper board. When wood is used the employment of short lengths is permitted by forming each band from a series of sections, as 22, 23, (Figs. 1 and 2) placed end to end. Under these circumstances, the ends of adjacent hoop sections may be connected, as by a wire staple 24 or all of the sections may be held in place upon the article to be protected, by an encircling loop 25, 26, of wire (Fig. 5).

While the articles, as 27, 28 and 29, selected for illustrations in Figs. 1 to 5 inclusive, each comprises a substantially cylindrical body 31 with a flange or bead 32 at its rim, and the corresponding hoops 10, 11, 14, 15 and 16, 17, are in each of these cases shown as being applied only to the said cylindrical body, these hoops are of sufficient thickness to project beyond the line of the outer edge of the said flange or bead 32. The flange or bead 32, even when wholly uncovered, as in Figs. 4 and 5, is nevertheless protected from contact with any upright surface or with similar articles of the same size having like protecting hoops. If desired, however, a further protection may be provided by applying upright staves 33 to the hoops, as 10, 11, (Figs. 1 and 3) at intervals about the same. When these staves are used, they are preferably of a length slightly greater than the height of the article to be protected. Without other covering for the top and bottom of the article they would accordingly serve to prevent contact of the ends of the article with large surfaces, but additional protection may be provided by applying cross pieces 34, 35, to the ends of the staves.

In all cases it is preferable to provide means for preventing vertical displacement of the said hoops or bands upon the body of the article. In the form of construction illustrated in Figs. 1, 2 and 3, the cylindrical body portion 31 of the article 27 is

formed with circumferential beads 36 (Fig. 3) one in line with each of hoops 12 and 13 and these hoops are grooved to receive the said beads. The staves 33 may accordingly be of such length that the cross pieces 34 and 35 are supported entirely out of contact with the ends of the article.

In Fig. 4 the wall of the article 28 is formed with annular grooves 37 and each 10 of the hoops 14 and 15 is formed with a bead 38 upon the inside of the same for entering one of the said grooves. In Fig. 5 the wall of the article 29 is formed with circumferential ribs 39 and 40 and one of the hoops, as 17, 15 is applied over the rib 40 and is grooved to receive the same. In this case the other hoop, as 16, is held against vertical displacement by being located between the rib 39 and the flange or bead 32 provided at the rim 20 of the article.

Protection for the bottom of the article may be provided without the use of the corresponding cross pieces, as 35 (Fig. 3) if desired, by so locating one of the hoops, as 25 15 (Fig. 4) that its lower edge extends substantially to the plane of or below the bottom of the article. A ring 41 may then be applied to the said hoop, as 15 to extend inwardly from the lower edge of the hoop 30 under the bottom of the article. Under these circumstances, the said ring and hoop will both be more firmly held upon the article if the bottom 42 of the article is circumferentially rabbeted, as at 43, to receive 35 the inwardly projecting portion of the ring. In the form of construction illustrated in Fig. 5, protection for the bottom of the article, as 29, is provided by wires, as 44 which extend diametrically across the same and 40 have their opposite ends applied to and secured upon the binding loop 26.

When staples, as 24, are employed for connecting the ends of adjacent loop sections, as 45 22, 23, additional protection against displacement of the corresponding hoop, as 11, may be obtained by making one arm, as 45 of the staple of greater length than the thickness of the hoop and providing the wall of the article, as 27 with recesses, as 50 46, for receiving the projecting end of the staple. In the case of a stoneware article, as 27, (Fig. 2) the said recesses, as 46, are, of course, readily formed during the manufacture of the same, before firing.

55 In the form of construction illustrated in Fig. 6 the protecting hoop 18 is applied to the article, as 47, from one end of the same and is held against removal by the provision of a series of interrupted ribs or flanges 48 and 49 formed upon the inside of the hoop and upon the outside of the article, respectively. Preferably these two sets of interrupted ribs are so located and proportioned that the ribs 48 upon the inside of the hoop 60 65 may be passed between the ends of adjacent

ribs 49 on the article and made to overlie the last mentioned ribs by partial relative rotation of the hoop and article. In this case protection for the bottom of the article is desirably also provided, as by applying 70 cross pieces 50 to one side of the hoop 18. If now the ribs 48 and 49 are each slightly inclined, as shown, to advance the hoop upon the article during the turning movement of the same and bring the cross pieces 50 firmly 75 against the bottom of the article, the said hoop and cross pieces will be firmly held upon the article and may be allowed to remain in place while the article is in use, if desired.

In Fig. 7 the several hoops or bands 19, 20 and 21, are applied directly to the article 30 and may be held in place thereon by a suitable adhesive. When this form of package is used some of the hoops, as 19 and 21 80 will desirably be shaped in cross section to conform in shape with the part of the article to which they are applied. As shown, the article 30 comprises the said cylindrical body 31 and marginal bead 32 and the hoops or bands 19 and 21 are respectively formed to fit over the bead 32 and over the lower edge or angle 51 at the bottom of the article.

I claim as my invention—

1. A stoneware package comprising, in combination, a jar or the like having an upwardly facing circumferential shoulder adjacent its lower edge, and a protecting hoop 95 extending about the jar above the shoulder and underneath the jar.

2. A stoneware package comprising, in combination, a jar or the like having oppositely facing circumferential shoulders, and a protecting hoop extending about the jar and engaging both shoulders, the outer diameter of the hoop being greater than the largest exterior diameter of the jar.

3. A package for frangible articles, comprising in combination an article having circumferential shoulders, protecting bands 110 engaging the exterior surface of said article between said shoulders, staves of greater length than the article secured to said bands, and heads secured to said staves.

4. A package for a stoneware or like article comprising, in combination, a split protecting band surrounding the article, means for securing the ends of said band together and means comprising interengaging members formed on the wall of the article and on the band for preventing axial displacement of the band.

5. A package for a stoneware or like article comprising, in combination, a protecting band surrounding the article and projecting beyond its end, means preventing axial displacement of the band comprising interengaging members formed on the wall of the article and on the band and a protecting element applied to one end of the band 125 130

and extending inwardly therefrom over the end of the article.

6. A package for stoneware or like article comprising, in combination, a protecting band of substantially uniform diameter throughout its length surrounding the article, interengaging means on the wall of

the article and band for preventing axial displacement of said band, and a protecting element secured to one end of said band and 10 extending inwardly therefrom over one end of said article.

RICHARD P. WHITE.
